BREAK-OUT BAR FOR DRILLING RIGS
Travis R. Wendell, P.O. Box 668, Rockport, Tex.
Filed Feb. 6, 1962, Ser. No. 171,461
12 Claims. (Cl. 29—283)

This invention comprises a novel and useful break-out bar for drilling rigs and more particularly pertains to a clamp for selectively holding against rotation and supporting a string of pipe to permit the addition of or removal of pipe sections therefrom and to lower the pipe into a bore.

The primary purpose of this invention is to provide a clamping device for gripping and supporting a string of pipe during the adding of or removal of some pipe sections therefrom.

A further object of the invention is to provide a break-out tool especially adapted for gripping and holding pipe of the thin walled type commonly employed for drilling shot holes for seismic and geophysical exploration.

A further object of the invention is to provide a device in accordance with the foregoing objects which will enable the applying of an adjustable tension on the pipe being gripped and held by the device.

A further object of the invention is to provide a device in accordance with the foregoing objects which shall include guide means to facilitate a lifting or lowering of the pipe being held by the implement.

A still further object of the invention is to provide a device in accordance with the immediately preceding object which shall include guide sleeves movably mounted on the opposite ends of the break-out bar to impart a guided action thereto.

And a final important object of the invention to be specifically enumerated herein resides in the revision of a clamping tool in accordance with the foregoing objects which shall incorporate therein a quick acting locking means for clamping the tool upon a pipe or releasing it therefrom.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view showing a preferred embodiment of the break-out tool in accordance with this invention the same being shown mounted over the drilling slot of an off shore drilling barge for supporting a pipe or casing string therethrough;

FIGURE 2 is a view in top plan of the tool, a portion of the clamping device being shown in section, the movable jaw being shown in its open position in dotted lines therein;

FIGURE 3 is a vertical transverse sectional view taken substantially upon the plane indicated by the section line 3—3 of FIGURE 2 and showing certain details of the locking means of the device, the latter being shown in full lines in its locked position and in dotted lines in its released position;

FIGURE 4 is a detail view in vertical transverse section taken substantially upon the plane indicated by the section line 4—4 of FIGURE 2 and showing in phantom the manner in which a pipe section is held in the tool; and

2

FIGURE 5 is a detail view in vertical longitudinal section taken upon an enlarged scale substantially upon the plane indicated by the section line 5—5 of FIGURE 1 and showing one of the guide means forming a part of the invention.

In the accompanying drawings, the break-out tool forming the subject matter of this invention is indicated generally by the numeral 10 and in FIGURE 1 is shown in operative position for holding a section 12 of a pipe or casing string as the latter is being manipulated through the drilling slot 14 of an off shore drilling barge 16. It will be appreciated, however, that the tool is useful in various other environments and drilling rigs.

As disclosed in these drawings and as set forth hereinafter, the break-out bar forming the subject matter of this invention is specifically adapted for the handling of thin walled pipes such as those commonly employed in the drilling of shot holes for seismic and geophysical operations. An important feature of the tool for this purpose is that it will securely grip with a variable and adjustable tension a thin walled pipe without danger of crushing or collapsing the same, thus performing functions which could not be effectively performed by conventional tongs or similar tools. However, certain features of the tool are adapted for use with strings of conventional pipe.

Referring now primarily to FIGURES 1 and 2 it will be observed that the tool 10 comprises an elongated bar having a central portion 20 of an arcuate configuration provided with a recess 22 which constitutes the fixed jaw of the break-out tool or clamping device. The opposite ends of the bar forming the main body of the tool terminate in elongated extremities 24 and 26 disposed in alignment with each other. Secured to the extremity 26 is a projecting rod 28 and the rod 28 and the extremity 24 constitute arms for supporting and maneuvering the implement as set forth hereinafter. As observed in FIGURE 2, the rod 28 is secured to the plate-like extremity 26 as by welding or the like 30. A pair of transverse angle members 32 and 34 are secured as by welding to the end portions 24 and 26, respectively, of the tool in order to support the latter in spaced relation to a support surface such as a deck of the barge as shown in FIGURE 1.

Cooperating with the fixed jaw formed by the central portion 20 of the elongated bar is a movable jaw 40 hingedly connected to the bar as by a pivot pin 42. The movable jaw is likewise provided with a concave portion 44 which is complementary to the portion 22 for gripping a pipe section 12 therebetween. At its extremity the movable jaw 40 is provided with an elongated end portion such as that indicated at 46 which comprises a handle and is disposed generally parallel to the arm 24. At its outward extremity, the handle 46 is provided with a laterally offset portion 48. As will be observed from FIGURE 2, the offset portion 48 at its junction with the handle 46 is slidably supported upon the cross member 34, being supported by a vertical flange 50 thereof in the same manner as the extremity of the portion 26.

A locking means is provided for effecting an adjustable lock. This locking means consists of a locking lever 52 having a bifurcated extremity 54 which is hingedly mounted as by pivot pins 56 to lugs 58 provided upon the arm 24. Thus, the lever 52 is mounted for swinging movement transversely of the longitudinal axis of

the tool, and towards and from the portion 48. Intermediate its ends, the bifurcated portions 54 are provided with a transverse pivot pin 60 upon which is journaled one end of a connecting link 62. The other end of the latter has an eye 64 which loosely embraces a pivot pin 66 which is perpendicular to the pin 60 and which pin 66, as shown in FIGURE 3, extends between the opposite sides of the U-shaped clamp 68 which comprises a clip. The link 62 preferably comprises a pair of sections connected by a knuckle joint 63 as shown in FIGURES 1 and 2. As will be observed, the clip 68 loosely straddles and receives therethrough the offset portion 48 of the handle 46. A thumb screw 70 threadedly engaged in the web 72 of the clip 68 engages the offset portion 48. The arrangement is such that when the clamp is swung between the full and dotted line position shown in FIGURE 3 it will be moved from its locking position to its releasing position. By adjustment of the screw 70, any desired tension may be imparted to the handle and the arm to vary the tension with which the jaws grip the pipe section therebetween.

A pair of guide means each indicated generally by the numerals 80 is movably received on the ends of the arms 28 and 24 of the tool. These guide means comprise sleeves 82 which are rotatably and axially slideable upon the arms. At the outer ends these sleeves are provided with outwardly projecting loops 84 having pins 86 therethrough and with these pins defining eyes which slidably receive guide wires or guy wires 88 which constitute stationary guide elements and may form a part of the drilling rig.

The arrangement is such that by means of the guide members 80 the tool is retained by the guide wires 88 for sliding movement thereon. The tool when clamped upon the pipe section will serve as a guide for the latter during the raising or lowering of the string or pipe 12.

The fixed and movable jaws of the tool are provided with semi-cylindrical plates or flanges 90 and 92, respectively, which are of sufficient area as to embrace the pipe along a considerable portion of the axial extent of the same. Thus the clamping action is distributed over a large area of the pipe thereby avoiding crushing or collapsing the relatively thin walled pipe for which this tool is specifically designed.

The tool serves not only to securely grip the pipe and thus enable additional sections to be removed or applied thereto in a conventional manner, but also serves to support the pipe and prevent it from dropping through the slot 14 when the pipe is lowered into the well bore.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A break-out tool for pipe strings comprising a bar having an arcuate, laterally bowed mid-portion defining a fixed jaw, arms projecting in substantial alinement with each other from the opposite ends of said mid-portion, an arcuate movable jaw complementary to and cooperating with said fixed jaw for clamping a pipe therebetween, a pivot connecting said movable jaw at one end thereof to said bar for swinging movement towards and from the latter, a handle rigidly attached to and projecting from the other end of said movable jaw and lying in spaced relation to said bar at one side thereof, locking means embracing said handle and pivotally connected to the adjacent arm of said bar and movable between locking and releasing positions for releasably retaining said jaws in clamping engagement upon a pipe, said locking means comprising a lever, a link pivoted to said lever and extending transversely of said handle and

bar, a clip pivoted to said link and embracing said handle.

2. The combination of claim 1, including adjusting means on said clip engaging said handle for adjusting the closed position of said jaws.

5 3. A break-out tool for pipe strings comprising a bar having an arcuate, laterally bowed mid-portion defining a fixed jaw, arms projecting in substantial alinement with each other from the opposite ends of said mid-portion, an arcuate movable jaw complementary to and cooperating with said fixed jaw for clamping a pipe therebetween, a pivot connecting said movable jaw at one end thereof to said bar for swinging movement towards and from the latter, a handle rigidly attached to and projecting from the other end of said movable jaw and lying in spaced relation to said bar at one side thereof, locking means embracing said handle and pivotally connected to the adjacent arm of said bar and movable between locking and releasing positions for releasably retaining said jaws in clamping engagement upon a pipe, said locking means comprising a lever, a link pivoted to said lever and extending transversely of said handle and bar, a clip pivoted to said link and embracing said handle, said lever having a bifurcated portion by which it is pivoted to and receives therein one end of said link.

25 4. The combination of claim 3, wherein said lever is pivoted by its bifurcated portion to said adjacent arm of said bar.

30 5. A break-out tool for pipe strings comprising a bar having an arcuate, laterally bowed mid-portion defining a fixed jaw, arms projecting in substantial alinement with each other from the opposite ends of said mid-portion, an arcuate movable jaw complementary to and cooperating with said fixed jaw for clamping a pipe therebetween, a pivot connecting said movable jaw at one end thereof to said bar for swinging movement towards and from the latter, a handle rigidly attached to and projecting from the other end of said movable jaw and lying in spaced relation to said bar at one side thereof, locking means embracing said handle and pivotally connected to the adjacent arm of said bar and movable between locking and releasing positions for releasably retaining said jaws in clamping engagement upon a pipe, transversely extending support members fixedly connected to the opposite ends of said bar.

35 45 6. A break-out tool for pipe strings comprising a bar having an arcuate, laterally bowed mid-portion defining a fixed jaw, arms projecting in substantial alinement with each other from the opposite ends of said mid-portion, an arcuate movable jaw complementary to and cooperating with said fixed jaw for clamping a pipe therebetween, a pivot connecting said movable jaw at one end thereof to said bar for swinging movement towards and from the latter, a handle rigidly attached to and projecting from the other end of said movable jaw and lying in spaced relation to said bar at one side thereof, locking means embracing said handle and pivotally connected to the adjacent arm of said bar and movable between locking and releasing positions for releasably retaining said jaws in clamping engagement upon a pipe, a pair of guide members mounted respectively upon said arms, said guide members having each a guide means for slideable engagement with a substantially stationary guide element.

50 55 60 65 7. The combination of claim 6, wherein at least one of said guide members is movably mounted upon its associated arm.

8. The combination of claim 7, wherein said last mentioned guide member comprises a sleeve axially and rotatably movable upon its associated arm.

70 75 9. A break-out tool for gripping pipe strings comprising an elongated bar having an arcuate, laterally bowed mid-portion defining a fixed jaw, a movable jaw pivoted to said bar and cooperating with said fixed jaw for clamping a pipe therebetween, spaced handles disposed in spaced side-by-side relation and each rigidly attached to one of

said jaws, locking means secured to and extending transversely of said handles for releasably retaining said jaws in gripping engagement upon a pipe, a pair of guide means mounted upon the opposite ends of said bar for sliding and guided engagement with a stationary guide element.

10. The combination of claim 9, wherein at least one of said guide means is movably mounted upon its associated end of said bar.

11. The combination of claim 9 wherein at least one of said guide means comprises a sleeve axially movable upon its associated end of said bar, said sleeve slidably engaging said stationary guide element.

12. The combination of claim 9 wherein at least one

of said guide means comprises a sleeve freely axially slid-able and rotatable upon its associated end of said bar, said sleeve slidably engaging said guide element.
